UNITED STATES PATENT OFFICE

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY

BLOWING DEVICE FOR ROCK DRILLS

Application filed July 19, 1927. Serial No. 206,859.

This invention relates to rock drills, but more particularly to a blowing device for fluid actuated rock drills of the hammer type.

One object of the invention is to permit the introduction of an uninterrupted volume of pressure fluid under full line pressure into the drill for removing the cuttings therefrom whenever the usual blowing devices provided for this purpose prove inadequate.

Other objects will be in part obvious and in part pointed out hereinafter.

In the drawings illustrating a practical embodiment of the invention,

Figure 1 is a longitudinal sectional elevation of a rock drill having the invention applied thereto and showing the blower valve in position to admit pressure fluid into one end of the valve chamber,

Figure 2 is a view similar to Figure 1 showing the blower valve closed,

Figure 3 is an end view of the valve chest partly in section, and

Figure 4 is a view taken through Figure 3 on the line 4-4 looking in the direction indicated by the arrows.

Referring to the drawings the invention is shown applied to a rock drill having a cylinder A in which is disposed a reciprocating hammer piston B to deliver blows of impact to a hollow drill steel C extending into a front head D. The piston B in this instance carries at its forward end a reduced extension or nose E, in the periphery of which are formed longitudinal flutes F which cooperate slidably with an internally fluted chuck mechanism designated by G for imparting rotary movement to the drill steel C.

Rotary movement of the piston is induced by rotation mechanism designated generally by H. The rotation mechanism H may be of a well known type in which a rifle bar J extends into and interlocks slidably with the piston B.

Preferably, the piston B is provided with a passage K through which a portion of pressure fluid admitted to the rearward end of the cylinder may flow to the drill steel and into the drill hole for the purpose of removing the cuttings therefrom.

A similar blowing effect is also obtained

upon the admission of pressure fluid to the front end of the cylinder, although during this stroke of the piston, a portion of the pressure fluid passes through the flutes F into the chuck G and thence through the hollow drill steel C into the drill hole.

In the construction shown, a valve chest L is disposed on the side of the cylinder A and has a bore O of uniform diameter therethrough to form a valve chamber P for the reception of a pressure fluid distributing valve Q. The rearward and front ends of the bore O are sealed by plugs R and S respectively and these plugs are bored to receive a bolt T whereby the plugs R and S are held securely in the ends of the bore O. The valve Q may be of a well known type having end heads U and V and a central head W, all of which are of the same diameter.

The central head W of the valve controls a port X of a supply chamber Y for intermittently admitting pressure fluid to the ends of the cylinder through inlet passages Z and b respectively, the inlet passages Z and b being so located that their inlet openings communicate with the valve chamber P between the heads V, W and U, W. The inlet passages Z and b also serve as passages for exhausting the fluid from the cylinder. The exhaust thus passes through the valve chamber P, that from the rearward end of the cylinder passes through an exhaust passage c in the valve chest, and is controlled by the head U of the valve. A similar exhaust passage d is formed in the forward end of the valve chest for the front end of the cylinder and is controlled by the head V of the valve.

Pressure fluid for actuating the valve is conveyed in this instance from the cylinder to the front and rear ends of the valve chamber P through kicker passages e and f respectively. The kicker passages e and f are controlled by the piston B and are so located that they will be uncovered thereby at the most advantageous period in the cycle of operations of the piston. For the best operation of the valve the kicker passages e and f are crossed and in this instance these passages communicate with the ends of the valve chamber P through ports g formed in the

heads U and V. The ports g serve both as admission and exhaust ports for the ends of the valve chamber so that pressure fluid admitted into one end of the chamber P may again return into the kicker passage from whence it may escape through leak ports h constantly communicating with the exhaust passages c and d.

Under certain operating conditions, depending upon the particular kind of rock being drilled, the pressure fluid admitted through the ordinary channels provided for cleansing the drill hole may be sufficient to prevent clogging of the drill hole. However, in drilling holes of a considerable depth and, in fact in most drilling operations, there are times when the intermittent blowing from the cylinder ends is inadequate to prevent the formation of a collar of detritus around the drill steel adjacent the cutting bit, and which collar often seriously retards the rotary movement of the drill steel.

In order to prevent an occurrence of this undesirable condition, means are provided in the present instance to selectively introduce an uninterrupted supply of pressure fluid into the drill holes at suitable intervals, thus at all times assuring a clean working surface for the cutting bit of the drill steel. The means whereby this is accomplished in the present instance comprises a blower valve j disposed transversely through a bore k in a projection o carried by the front valve chamber plug. At one end of the valve j is a lever p whereby the valve j may be manipulated.

Preferably, a flange q is formed at the juncture of the lever p and the valve j to bear against the side of the projection o for holding the valve j against endwise movement in one direction. In order to hold the valve j against such movement in the opposite direction, a collar r is disposed on the projecting end s of the valve j and secured thereto by means of a pin t.

The blower valve j in this instance has a longitudinal groove u suitably located to establish communication between a passage v in the plug S which leads to the forward end of the valve chamber P and a passage w leading from the supply chamber Y to the bore k.

Any suitable means may be provided for limiting the degree of rotation of the blower valve j and also to hold said blower valve in its closed and open positions. The means provided for this purpose in the present instance comprise a spring pressed plunger x located in the plug S and adapted to engage suitably spaced depressions y in the peripheral surfaces of the valve j. Such depressions may be of considerable depth so that their outer walls may engage the plunger x to act as a stop for the valve, and the depressions y may be connected by a shallow groove z through which the end of the plunger x may travel.

The operation of the device is as follows: Ordinarily with the blower valve j in the position shown in Figure 2, the valve Q and the piston B will function in their normal manner, and a portion of the pressure fluid admitted through the front inlet passage Z will, after the piston B approaches the rearward end of the cylinder, pass through the kicker passages f and throw the valve forwardly. The remainder of the pressure fluid in the front end of the cylinder will then escape through the passage Z, the valve chamber P, between the heads W and V, and thence through the exhaust port D to the atmosphere.

A similar sequence of events will occur during the forward stroke of the piston, in which case the pressure fluid is exhausted through the inlet passage b between the heads W and U and through the rearward exhaust passage c to the atmosphere.

During what may be termed the normal operation of the drill, a portion of the pressure fluid escapes through the flutes and through the chuck G and the drill C into the drill hole to blow the cuttings therefrom on each rearward stroke of the piston. On the forward stroke of the piston B a portion of the pressure fluid admitted into the rearward end of the cylinder will flow along the rifle bar J through the passage K, the chuck G and thence into the drill hole through the drill steel, thus also causing a certain blowing effect while the piston B is travelling forwardly.

Usually while the drill hole is comparatively shallow, or when drilling rock of ordinary hardness, the puffs of pressure fluid admitted into the drill hole upon each stroke of the piston are adequate for maintaining reasonably favorable conditions in the drill hole. If, however, an accumulation of cuttings should occur therein to an extent which would not yield to these intermittent puffs of pressure fluid, the blower valve j may be opened to an extreme position and pressure fluid will then be admitted directly from the supply chamber Y through the passages W and b and the groove u into the front end of the valve chamber P to act against the valve Q, and hold said valve immovable in the rearward end of the valve chamber. With the valve Q in this position, the front inlet passage Z will be in direct communication with the supply chamber Y so that a constant flow of pressure fluid may pass into the front end of the cylinder to hold the piston B immovable in the rearward end of the cylinder. Pressure fluid may then flow from the front end of the cylinder through the flutes F into the drill hole in the manner in which it is ordinarily admitted to the drill steel during the rearward stroke of the piston.

After the desired blowing effect has been obtained the blower valve j may again be

rotated to its closed position and the reciprocating elements of the drill may again function in their normal manner.

As will be observed, when the piston B is in its extreme rearward position during the blowing operation, the kicker passage f will be uncovered so that pressure fluid may also pass into the rearward end of the valve chamber P. Such pressure fluid however, will be of lower value than line pressure since the said kicker passage g is in constant communication with the atmosphere through the rearward leak port h, the valve chamber P and the exhaust port e.

15 I claim:

In a fluid actuated rock drill, the combination of a cylinder, a piston in the cylinder having a forward fluted extension, a valve chest for the cylinder having a valve chamber and a pressure fluid supply chamber, plugs forming closures for the ends of the valve chamber, inlet passages leading from the valve chamber to the ends of the cylinder, a distributing valve in the valve chamber controlling communication between the supply chamber and the inlet passages, a passage leading from the supply passage through the valve chest and the front plug to the front end of the valve chamber, and a blower 25 valve disposed transversely through the front plug controlling said passage, said blower valve being rotatable to admit pressure fluid into the front end of the valve chamber to hold the distributing valve immovable in the rear end of the valve chamber and permit a constant flow of pressure fluid from the supply chamber to the front end of the cylinder thence along the fluted extension into a drill 30 steel.

40 In testimony whereof I have signed this specification.
